UNITED STATES PATENT OFFICE.

CHARLES E. BALL AND SAMUEL H. BALL, OF IRWIN, CALIFORNIA.

SCRAPER.

Application filed November 17, 1924. Serial No. 750,349.

Our invention relates primarily to a scraper such as is used for road construction, land leveling, etc., of the character described and claimed in Patent No. 1,522,937, 5 dated January 13th, 1925, and the object is to provide certain new and useful improvements therein. In the use of the mechanism in the above patent it was found that by arranging the scrapers so as to be at an 10 angle with the front end uppermost while carrying a load, and providing a gate for the rear portion of the scrapers to be released when it was desired to unload the same, that a much superior device was produced which eliminated spillage, increased 15 speed of operation and thereby greatly reduced the cost of operation.

It is the object of our invention to provide a scraper or scrapers mounted on a 20 frame supported at a suitable distance by wheels and a carrying mechanism whereby the scrapers (one or more) may be lowered and loaded in the usual manner and then elevated and transported to the desired place 25 of deposit, with a suitable gate provided to prevent the accidental spillage of the load at the front end, and with a releasable gate closure at the rear end of the scraper to allow of dumping without the necessity of tipping the same. Suitable mechanism is also 30 provided to control the angle at which the bowl is raised, whereby the load may be deposited in one place or may be spread to level as desired.

35 Other objects and advantages will appear hereinafter and, while we have shown and will describe the preferred form of our invention, we wish it specifically understood that we do not limit ourselves to such preferred form but that various changes and adaptations may be made therein without departing from the spirit of our invention.

In the drawings accompanying and forming a part hereof:

45 Figure 1, is a side elevation of our improved device.

Figure 2, is a top plan of Figure (1).

Figure 3, is a top plan, on an enlarged scale, of the scraper control mechanism.

50 Figure 4, is a side elevation of Figure (3).

Figure 5, is an enlarged detail view showing the raising and lowering mechanism of the scrapers.

55 Figure 6, is a top plan of one of our scrapers.

Figures 7 and 8 are rear elevations of one

of our scrapers showing the rear gate locking and releasing mechanism.

Figure 9, is an enlarged side elevation of our rear axle braking mechanism.

Figure 10 shows a detail of construction.

Referring to the drawings our device comprises a substantially rectangular frame 10 supported at its front end by a pivotal axle 11, which axle is supported at each end by 65 wheels 12 and 13. Extending transversely of frame 10 at a short distance from the rear end is an axle 14 supported near each end by bearings extending downwardly from frame 10, and mounted upon the ends 70 of said axle are wheels 15 and 16 provided with the usual ratchet mechanism. Revolvably mounted at its ends in bearings 17 and 18 to extend transversely of frame 10 is a drive shaft 19 one end of which extends beyond bearing 17. Rigidly mounted upon this projecting end is a sprocket 20 which is connected by a chain 21 to a sprocket 22 rigidly mounted upon axle 14 whereby rotation of said axle will be imparted to shaft 19. 75 Revolvably mounted at their ends in bearings 23 and 24 extending upwardly from frame 10 are the bowl elevating shafts 25 and 26 which extend transversely of the frame 10. Rigidly mounted upon these shafts at a 80 short distance from the inner sides of frame 10 are spur gears 27 and 28.

Rigidly mounted upon shaft 25 at the inner side of gear 28 is a sprocket 29 which is connected by a chain 30 to a sprocket 31 90 loosely mounted upon shaft 19. A clutch 32 of any suitable construction provides means for locking sprocket 31 to shaft 19 whereby rotation of shaft 19 may be imparted to shaft 25. Rigidly mounted upon shaft 26 95 at the inner side of gear 27 is a sprocket 33 which sprocket is connected by a chain 34 to a sprocket 35 loosely mounted upon shaft 19. A clutch 36 of any desired construction provides means for locking sprocket 35 to 100 shaft 19 whereby rotation of shaft 19 may be imparted to shaft 26.

Extending transversely of frame 10 and secured at its ends thereto immediately in front of shaft 19 is a cross member 37 and 105 upon this cross member are pivotally mounted bell crank levers 38 and 39 which are operatively connected to clutch levers 40 and 41 of clutches 32 and 36 respectively. The free end of bell crank lever 38 is connected by a rod 42 to the upper end of an arm 43 which arm is rigidly mounted upon

a transverse rocking shaft 44 mounted at its ends in frame 10. The upper end of arm 43 is pivotally connected to one end of a rod 45 the other end of which extends forward-
 5 ly and is pivotally connected to the upper end of an arm 46. This arm is loosely mounted at its lower end upon a transverse shaft 47 turnably mounted at its ends in the sides of frame 10. An operating handle 48
 10 extends forwardly from the front end of arm 46 about centrally of its length and provides means for controlling the rotation of shaft 25. The free end of bell crank lever 39 is pivotally connected by a rod 49 to the
 15 upper end of an arm 50. The other end of arm 50 is rigidly mounted upon shaft 47. Arm 50 is provided with an operating handle 51 by means of which the rotation of shaft 26 is controlled.

20 Our bowl elevating means comprise vertically extending bars 52 the lower ends of which are pivotally connected to the bowls 54 on the inner sides thereof by pivots 55. The upper ends of bars 52 are provided with
 25 rack bars 58 the teeth of which are in operative engagement with the teeth of gears 27 and 28. U-shaped brackets 59 loosely mounted upon shafts 25 and 26 serve to hold racks 58 positioned in operative engagement
 30 with gears 27 and 28.

Our bowls 54 are substantially U-shaped in end elevation and are composed of the bottom wall 61 and the side walls 62. Pivotally connected at one of their ends to the outside sides of the side walls 62 of the bowls upon the pivots 55 of the elevating bars 52 are links 64 the other ends of which are pivotally mounted upon studs 66. Studs 66 are adjustably mounted in apertures 68 provided in downwardly depending brackets 70 and 71 secured to the sides of frame 10. Pivotally connected at their lower ends to the outer sides of the side walls 62 of the bowls 54 at the top of the rear wall are links
 45 72 the other ends of which are pivotally mounted upon studs 74 adjustably mounted in apertures 76. Apertures 76 are provided in vertically extending members 77 secured to the frame. It will be here specifically
 50 noted that by providing a plurality of apertures 68 and 76 the pivotal ends of links 64 and 65 and 72 may be adjusted to vary the angularity of the cutting edge of the bowls to suit varying types of soil and earth.

55 Connecting the upper extremity of the side walls 62 of the bowls 54 is a rod 78 and upon this rod is pivotally mounted one end of the rear end gate 79 which gate is of a configuration to snugly fit the rear end of said bowl. Extending rearwardly from the bottom wall 61 bowl 54 is a catch 80 provided with a notch 81 and rigidly secured at its upper end to the outer face of gate 79 is a latch 82. This latch is of resilient
 60 material (preferably spring steel) and of a width to fit within notch 81 and having its lower end turned at a right angle to snugly fit beneath catch 80 to securely hold gate 79 in its closed position. Loosely mounted in the lower end of latch 82 to extend parallel with gate 79 is one end of a stud 83 the other end of which is pivotally mounted in the free end of the short leg 84 of a bell-crank releasing lever 87. Lever 87 is pivotally mounted upon gate 79 by means of a pivot 86 and projects through a guide strap 85 on the gate. To the free end of the longer leg of the lever is connected one end of an operating cable 88 which passes over grooved wheels 89 suitably mounted in frame 10 and thence to the front end of the machine a termination near the driver's seat 90. Pivotally mounted upon rod 78 at the outer ends of gate 79 are arms 91 and 92 which extend forwardly and support 83 upon their outer ends the front end gate 93. Gate 93 is preferably formed from sheet metal and has its ends bent to lie parallel with the sides of bowl 54 and these sides are pivoted to the ends of arms 91 and 92.
 90 It will be specifically noted that the front portion of gate 93 is positioned to extend angularly forward relative to the bottom of bowl which construction is provided so that said gate when closing will act its 95 way through any earth which may be overhanging the front end of said bowl.

95 Cables 94 and 95 are secured at one of their ends to gates 93 and at their other ends are loosely mounted upon shafts 44 and 47. 100 These cables are of a length sufficient only to hold the gates a certain distance from the ground. Rigidly mounted upon the outer ends of shafts 25 and 26 at one side of frame 10 are ratchet wheels 96 and 97 and pivotally mounted upon frame 10 are pawls 98 and 99 adapted for engagement with said ratchets to prevent the reverse rotation of shafts 25 and 26. They thus serve to hold the bowls elevated when desired. The lower 110 end of pawl 98 is connected by a rod 100 to a crank 101 rockably mounted at the front of the machine, which crank is provided with a foot pedal 102 by means of which said pawl is disengaged from its ratchet. 115 Pawl 99 is connected by a rod 103 to a similar crankshaft 104 provided with a foot pedal 105. Springs 106 act to normally hold said pawls in operative positions. The upper ends of bars 53 are provided with right angled lips or projections 107 and in these projections are slidably mounted rods 108 which extend upwardly and are slidable vertically. The upper ends of rods 108 are threaded and provided with nuts 109 and 120 110. The lower ends of rods 108 are pivotally connected to one end of links 111, the other ends of which links are rigidly mounted upon rocking shafts 44 and 47 respectively so that as said shafts 44 and 47 are rocked 125 115

120 110

125 115

130 120

the outer ends of said links will slide rods 108 vertically. When the clutch control handle 48 for instance is raised to cause the corresponding clutch 32 to be thrown in to drive the shaft 25 and cause the rack 58 and bowl 54 to be raised, the projection 107 on said rack will after some movement of the latter engage the nut 110 on the adjacent rod 108 and will raise the same. This movement through the connecting link 111 will rotate the shaft 44 and gradually cause the handle 48 to be depressed, thus throwing the clutch 32 out and automatically discontinuing the raising of the bowl. The distance to which the bowl will be thus raised depends on the position at which the nuts 109 and 110 are set on the rod 108. Rigidly mounted upon the ends of shafts 25 and 26 at the outer side of frame 10 and on the side opposite to ratchet wheels 96 and 97 are brake drums 112 and 113 and passing around these drums are brake bands 114 and 115 one of the ends of which are mounted upon studs 116 extending from the side of frame 10. The other ends of bands 114 and 115 are secured to slotted members 117 each provided with a longitudinal slot 118. Loosely mounted in slots 118 are studs or pins 119 which project outwardly from the upper end of arms 120. The other ends of arms 120 are rigidly mounted upon shafts 44 and 47 whereby when said shafts are rocked forwardly a sufficient distance bands 114 and 115 are caused to frictionally engage the respective drums 112 and 113. This arrangement permits the shafts 25 or 26 to be held immovable after the corresponding clutch's are disengaged, by a further depression of the handles 48 or 51. This prevents the racks and bowls from any undesired raising out of the ground of themselves after they have been lowered to the proper scraping angle and depth. At the same time, owing to the slots in the members 117, the brakes remain released under all ordinary operating conditions.

Rigidly mounted upon axle 14 at the inner side of wheel 16 is a brake drum 121 and engaging the outer periphery of said drum is a brake band 122. One end of band 122 is provided with an adjustable clevis 123 which clevis is pivotally mounted upon an operating bar 125 intermediate its ends. Bar 125 is pivotally mounted at its lower ends between the lower ends of links 126 by means of stud 127. The upper ends of links 126 are pivotally mounted in frame 10. The other end of band 122 is pivotally mounted upon stud 127. The upper end of bar 125 is pivotally connected to one end of a pull rod 128 which extends forwardly therefrom and terminates in a clevis 129. Clevis 129 is pivotally connected to the upper end of an arm 130 rigidly secured upon one end of a rod 131 rockably mounted in a bearing 132. Rod

131 is provided at its inner end with an upstanding foot pedal 133 by means of which the brake is applied.

Having described our invention what we claim is:

1. A scraper including a frame supported from the ground, a scraper bowl, drive means for raising the bowl, such means including a vertical rack connected to the bowl, a shaft, a pinion on the shaft engaging the rack and a driven shaft operatively connected with the pinion shaft; a clutch for controlling the driving of the pinion shaft, hand means for releasing the clutch, and means actuated by the vertical movement of the rack a predetermined distance for also releasing the clutch, said means including a shaft connected to the hand means and rotated thereby, a vertical rod, a lateral projection on the rack through which the rod passes, an adjustable member on the rod above the projection to be engaged thereby, and a link between the lower end of the rod and the shaft and fixed to the latter, said rod when raised by engagement of the rack projection with the adjustable member thereon causing the shaft to be rotated in a clutch releasing direction.

2. A scraper including a frame supported from the ground, a bowl normally disposed below the frame, the sides of the bowl converging upwardly from both ends to form a substantially central apex, means applied to the bowl for raising the same, further means between the bowl and frame whereby with such upward movement the bowl will tilt rearwardly, a normally closed but releasable gate hinged onto the bowl at the apex thereof and extending downwardly to the rear lower end of the bowl, a front gate pivoted onto the bowl and projecting thence forwardly, and upwardly yieldable means holding said front gate in diverging relationship to the forward edges of the sides of the bowl when the latter is in its normal position adjacent the ground.

3. A scraper including a frame supported from the ground, a bowl normally disposed therebelow, a single rigid and forwardly extending link pivoted onto the bowl toward its forward end and onto the frame ahead of the bowl, a vertical member pivoted onto the bowl in common with the link and projecting upwardly therefrom, means applied to said member for moving the same vertically, and another rigid link pivoted onto the bowl adjacent its rear end and extending thence upwardly to an immovable pivotal connection with the frame.

4. A scraper including a frame supported from the ground, a bowl normally disposed therebelow, a single rigid and forwardly extending link pivoted onto the bowl toward its forward end and onto the frame ahead of the bowl, a vertical member pivoted onto

- the bowl in common with the link and projecting upwardly therefrom, means applied to said member for moving the same vertically, and another rigid link pivoted onto the bowl at its rear end and a predetermined distance from the bottom of the bowl, and extending thence upwardly and forwardly to an immovable pivotal connection with the frame.
- 5 10 5. A scraper including a frame supported from the ground, a bowl normally disposed below the same, means applied to the bowl for raising the same, further means between the bowl and the frame whereby with such movement the bowl will tilt rearwardly, a front endgate for the bowl, means whereby said gate will automatically cooperate with the front of the bowl to close the same only when the bowl is thus tilted,
- 15 20 a rear endgate mounted on the bowl tending to automatically swing open when the
- bowl is tilted, and releasable latch means normally preventing such swinging movement of the rear endgate.
6. A scraper including a frame, a bowl, means for raising the bowl, means between the frame and bowl for causing the latter when raised to tilt rearwardly, the sides of the bowl at the rear end extending substantially at right angles to the bottom of the bowl for a certain distance and then sloping upwardly and forwardly for a further distance, and a releasable end gate extending between the sides from the bottom of the bowl to adjacent the top of said sloping portion and being pivoted at its upper end onto the bowl.

In witness that we claim the foregoing we have hereunto set our hands this 6th day of August, 1924.

CHARLES E. BALL.
SAMUEL H. BALL.
